UNITED STATES PATENT OFFICE.

BARNETT B. WHALEY, OF BROOKLYN, NEW YORK.

TOY.

SPECIFICATION forming part of Letters Patent No. 554,555, dated February 11, 1896.

Application filed May 13, 1895. Serial No. 549,157. (No model.)

To all whom it may concern:

Be it known that I, BARNETT B. WHALEY, a citizen of the United States, residing at Brooklyn, in the county of Kings and State 5 of New York, have invented new and useful Improvements in Toys, of which the following is a specification.

This invention relates to a toy which can be effectively used in producing soap-bubbles; 10 and the invention resides in the novel features of construction set forth in the following specification and claims, and illustrated in the annexed drawings, in which—

Figure 1 is a sectional side elevation of the 15 toy. Fig. 2 is a side elevation of a modification. Fig. 3 is a detail view of a valve. Fig. 4 is a detail view of a further modification. Fig. 5 is a detail view of a pipe-bowl. Fig. 6 shows a further modification.

20 The bulb or pump 1 has passages forming an inlet 2 and an outlet 3. The well-known elastic or compressible bulb is serviceable for this purpose, though of course various forms of pumping or forcing arrangement could be 25 employed. The inlet and outlet have valve-seats 4 against which sit the valves 5 formed of disks, as seen in Fig. 3, each disk having a lip or projection 6. A screw or tube 7 is screwed to the inlet and a tube 7' to the outlet, the inlet and outlet being suitably tapped or threaded for this purpose. The outlet-screw 7' and inlet 2 have each a rim or projecting flange 8 of such size that the disk part 5 of the valve can enter the ring-like 35 space formed by the flange; but said flange, when the tube 7' is screwed into place, will clamp or hold the lip part 6 of the valve, so that the disk part 5 being held or supported by the lip 6 cannot become displaced, while 40 the lip is thin or flexible enough to allow the disk 5 to play or swing from and against the valve-seat as the respective passage is to be opened or closed. The operation of the bulb or pump 1 will thus cause air to enter through 45 inlet 2 and to be ejected through outlet 3. To each screw 7 and 7' is connected or slipped a tube or coupling 9, the coupling at the inlet side being provided with a smoke-supplier, such as a cigar or cigarette holder A, 50 having a cigar or cigarette B, Fig. 1, or a tobacco-pipe A', Fig. 2. At the outlet side the coupling 9 is provided with a pipe 10.

The pipe 10 being dipped into soapsuds, as customary when blowing soap-bubbles, and the pump 1 being then worked, air and smoke 55 will enter through inlet 2 and will be ejected through outlet 3 and pipe 10, so that the resulting soap-bubble will contain smoke. When such a bubble is caused to float off and break, the smoke escaping on the rupture of 60 the bubble will give somewhat the effect of a shell exploding on a battlefield, thus producing startling effects and affording amusement.

To prevent burns or accidents from the 65 lighted cigar or cigarette B, a protector C, such as a sheath or non-combustible tube, can be slipped or placed about the cigarette or cigar. Similarly the pipe A' for burning tobacco can be provided with a protector C', 70 consisting of a cover or perforated plate.

In place of smoke it is evident that other substance or vapor—as, for example, perfume—might be allowed to enter from a suitable sponge or absorbent into the inlet 2 and 75 thence into the bubble. It is also to be noted that the bowl or exit 10, instead of being used to form soap-bubbles, could be used as an inhaler to suitably deliver smoke or fumes— 80 as, for example, from a cubeb cigarette, the fumes of which are to be inhaled through the nose.

The bulb or forcing-chamber 1 might of course be given various shapes or designs. In order to prevent the valves or disks 5 from 85 becoming hard or deteriorated by the smoke and vapor, I make the same of mica, which I have found is durable and unchangeable and at the same time sufficiently elastic to yield and to form an effectively closing valve. 90

The inlet 2 when not provided with any smoke or other supply will allow plain air to pass through the device to be used for forming plain soap-bubbles or otherwise utilized.

The bowl of pipe A' is shown with a flange 95 13 against which sits the cover C', and in case such cover C' should not fit properly a packing 14 inserted between the flange 13 and flange 15 will cause said cover to firmly sit in place. Likewise the pipe-bowl 10' is shown provided with a flange 13, and when said bowl 10' is held in upright position while a bubble is blown, Fig. 5, the flange 13 will prevent said bubble from sagging or will keep said

bubble in upright position. Said bowl 10' may also be provided with a cover 16 having a plurality of holes, which when the bowl is dipped into soapsuds and air ejected therefrom will cause a variety or plurality of bubbles. Said bowl 10', if seen fit, can have a packing like the packing 14 on bowl A'. A clamp or spring 17 adapted to clamp or engage against the interior of the bowl has a stem or support 18 from which can be suspended or on which can be supported a figure 19, as of a man, or of any object, and the soap-bubble when blown will form about such figure. To properly support the figure in the bubble the stem or support 18 should extend centrally along in the bowl and the latter should be as near as possible of cylindrical bore.

By having the stem or support extended through the bottom of the pipe-bowl, as shown by the stem 18', Fig. 4, having handle 20, the bubble can be blown while the figure or figures 19 are in the bowl, and after the bubble is completed the figure 19 can be moved or slid by handle 20 into the bubble.

When the cover 16 is used with stem 18, the cover 16 should have a central opening for the passage of the stem.

In order to have the bubbles properly adhere to the bottom or outer face of the cover, said outer face should be roughened, the roughening being readily obtained by piercing the holes in the cover in an outward direction, so that jagged portions of the cover will lie adjacent to the openings.

The spring for clamping the interior of the bowl can be formed with a gage 21, which gage sitting against the bowl-bottom as the spring 17 is forced into place will align the support 18 with the bowl-axis, or in other words will bring the support 18 into central position relatively to the bore of the bowl. This gage 21 can, however, be omitted if desired.

In order to prevent ashes or foreign matter passing in through inlet 2 or to the inlet-valve, a sieve or strainer 22 can be properly applied at said inlet.

In Fig. 6 a support 18² is shown adapted to engage or be suspended from a bowl-cover 16, said support or stem 18² having a bent or attaching portion 23 suitably shaped—as, for example, approximately screw-threaded—so that said attaching portion 23 can be readily inserted into the central hole of cover 16, even when said cover is on the bowl.

What I claim as new, and desire to secure by Letters Patent, is—

1. A toy for producing soap-bubbles, consisting of a bulb or forcing-chamber 1 provided with a screw-threaded inlet and a screw-threaded outlet, tubular screws 7 and 7' engaging said inlet and outlet, flanges interposed respectively between the screw-threaded inlet and the screw-threaded outlet, and the said tubular screws, valves having

lips held by said flanges, a coupling on each 65 tubular screw, a smoke-supplier connected to one of the couplings, and a pipe-bowl connected to the other coupling, substantially as described.

2. A toy for producing soap-bubbles, 70 consisting of a bulb 1 provided with a screw-threaded inlet and a screw-threaded outlet, tubular screws engaging said inlet and outlet, flanges interposed respectively between the inlet and outlet and the said tubular screws, 75 valves having lips held by said flanges, a coupling mounted on each tubular screw, a pipe-bowl connected to one of the couplings, a smoke-supplier connected to the other coupling, and a sheath or tubular protector arranged over the smoke-supplier substantially as and for the purposes described.

3. A toy for producing soap-bubbles, 80 consisting of a bulb or forcing-chamber 1 provided with a screw-threaded inlet and a screw-threaded outlet, tubular screws 7 and 7' engaging said inlet and outlet, a sieve or strainer at said inlet, flanges interposed respectively between the screw-threaded inlet and the screw-threaded outlet and the said tubular 90 screws, valves having lips held by said flanges, a coupling on each tubular screw, a smoke-supplier connected to one of the couplings, and a pipe-bowl connected to the other coupling, substantially as described. 95

4. A bulb or forcing-chamber provided with passages forming an inlet and an outlet, valves for said passages, a pipe-bowl connected to said outlet, and a suspending device provided with a spring for clamping or grasping the interior of the bowl substantially as described. 100

5. A bulb or forcing-chamber provided with passages forming an inlet and an outlet, valves for said passages, a pipe-bowl connected to the outlet, and a suspending device, composed 105 of a hook or arm, extending from the pipe-bowl and provided with a spring for retaining, and a gage for centering, the hook or arm in the bowl, substantially as described.

6. A toy for producing soap-bubbles comprising a pipe-bowl and a suspending device adapted to engage the interior of the bowl substantially as described. 110

7. A toy for producing soap-bubbles, 115 consisting of a pipe-bowl, and a suspending hook or arm extending outwardly from the center of the bowl-opening and constructed to support an object, whereby the object suspended by the hook or arm will be inclosed by a bubble issuing from the pipe-bowl, substantially 120 as described.

In testimony whereof I have hereunto set my hand in the presence of two subscribing witnesses.

B. B. WHALEY.
